UNITED STATES PATENT OFFICE.

BENJAMIN BRAZELLE, OF ST. LOUIS, MISSOURI.

APPARATUS FOR MANUFACTURING GAS.

SPECIFICATION forming part of Letters Patent No. 365,294, dated June 21, 1887.

Application filed November 2, 1886. Serial No. 217,786. (No model.)

To all whom it may concern:

Be it known that I, BENJAMIN BRAZELLE, of St. Louis, in the county of St. Louis and State of Missouri, have invented certain new and useful Improvements in Apparatus for the Manufacture of Gas, of which improvements the following is a specification.

My invention relates to the manufacture of gas by the decomposition of steam in its passage through a mass of incandescent carbonaceous material; and its object is to provide an apparatus of simple, compact, and comparatively inexpensive construction, in the operation of which the action of the fuel shall be effectively and economically exerted in the exertion of its decomposing function, as well as advantageously utilized in the generation of steam.

To this end my invention, generally stated, consists in certain novel combinations, including a furnace or combustion-chamber inclosing two compartments separated by a dividing wall or partition, a steam-boiler located above and subject to the action of the heat of said furnace, a grate fixed in the furnace, a valve governing the passage of the products of combustion through the boiler-tubes, and a pair of regenerator-chambers communicating with the furnace below its grate and provided with valves whereby the products of combustion may be passed alternately through the regenerator-chambers.

The improvements claimed are hereinafter fully set forth.

35 In the accompanying drawings, Figure 1 is a vertical central section through an apparatus embodying my invention, and Fig. 2 a horizontal section through the same at the line xx of Fig. 1.

40 In the practice of my invention I provide a furnace or combustion-chamber, 1, which is preferably of cylindrical form and is composed of fire-brick inclosed in a gas-tight casing of boiler-iron. The furnace is divided by a vertical wall or partition, 2, of fire-brick extending upwardly from its bottom for the major portion of its height into two compartments, 3 4, each of which is provided with an upper charging-door, 5, and a draft-door, 6, at or 45 near its bottom. The top of the furnace, which is open, is contracted or reduced in diameter to form a throat, 7, and a steam-boiler, 8, is

fixed upon its top, completely surrounding and inclosing the throat 7. A series of fire-tubes, 9, extending from a lower tube sheet, 10, to 55 an upper tube-sheet, 11, communicate at their lower ends with the throat 7 and at their upper ends with the uptake or discharge flue 12 of the boiler, which is governed by a valve, 13.

The furnace is provided with a continuous 60 tubular grate, 14, composed of a pipe or connected series of pipes extending across the lower portion of the compartments 3 4, said grate communicating by a connection passing through the wall of one of the compartments 65 with a feed-water pipe, 15, and at its opposite end with a discharge-pipe, 16, leading through the wall of the other compartment to a connection with the boiler 8 near the bottom thereof. The compartment 4 communicates by a passage, 17, below the grate 14 with a vertical regenerator-chamber, 18, formed of fire-brick inclosed in a gas-tight iron casing and having a valve, 19, at top, the interior of said chamber above the passage 17 being filled with a 75 checker-work or loosely-piled mass of fire-brick, 20, into the upper portion of which a pipe, 21, governed by a valve, 22, leads from the steam space of the boiler 8. The compartment 3 communicates by a passage, 23, below 80 the grate, with a similar regenerator-chamber, 24, filled with checker-work 25, and closed at top by a valve, 26, controlling a gas-discharge pipe, 27, leading to a suitable gas holder or receiver. An air-blast pipe, 28, fitted with a 85 valve or gate, 29, is led into the upper portion of the regenerator-chamber 24.

In operation, water being supplied to the grate 14, and to a proper level in the boiler 8, and the combustion-chamber 1 being charged 90 with fuel which is ignited, the valve 13 and draft-doors 6 are opened, and steam is generated in the boiler to a sufficient pressure to operate a blower. The valve 13 and doors 6 are then closed, and the valve 19 of the regenerator-chamber 18 and valve 29, controlling the air-blast pipe 28 of the regenerator-chamber 24, are opened. Air is then forced in from the blast-pipe 28 to the regenerator-chamber 24, and through the passage 23 into the compartment 3 of the combustion-chamber 1, passing upwardly through the fuel in the compartment 3, and thence over the top of the dividing-wall 2, downwardly through the fuel in the

compartment 4, and through the passage 17 into the regenerator-chamber 18. The air-blast is continued until the fuel in the combustion-chamber has been brought to and maintained in an incandescent condition for a sufficient period to raise the checker-work 20 of the regenerator-chamber 18 to a high degree of heat by the action of the products of combustion, which pass through the same and escape at the valve 19. The regenerator-valve 19 and air-blast valve 29 are then closed, and the gas-discharge valve 26 being opened, steam from the boiler is admitted to the heated checker-work 20 by the valve 22, and, passing downward through the same and upward and downward through the incandescent fuel in the compartments of the combustion-chamber, is decomposed, the resultant gases, in their passage through the checker-work 25 of the regenerator-chamber 24, heating the same to a high degree, and being themselves correspondingly reduced in temperature before passing out through the gas-discharge pipe 27. After a period has elapsed sufficient to require a renewal of the blast on the fuel, the valves 26 and 22 are closed, and the valves 19 and 29 being opened, the operation first described is repeated. The feed-water is pumped into the hollow grate 14 from the pipe 15, and in circulating through the grate becomes heated to a high degree before passing therefrom by the discharge-pipe 16 to the boiler, and generation of steam is maintained by the direct action of the radiant heat of the combustion-chamber upon the boiler during the entire course of the operation.

The state of the art to which my invention relates indicates that a generating-chamber divided into separate compartments, a generating-chamber and separate regenerators communicating therewith, and a generating-chamber discharging its products of combustion continuously through the tubes of a superposed steam-boiler were severally known prior to my invention, and such devices, therefore, I hereby disclaim. I am not, however, aware of a prior construction such as herein set forth and claimed, or equivalent means, for preliminarily applying the heat of the combustion-chamber in the rapid generation of steam by passing the products of combustion through the boiler-tubes and thereafter utilizing the direct radiant heat of the combustion-chamber during the decomposition of steam for the continuous generation thereof.

The advantages attained by my invention are the provision of a compact and comparatively inexpensive structure and an economical utilization of the fuel employed.

I claim as my invention and desire to secure 60 by Letters Patent—

1. In an apparatus for the manufacture of gas, the combination, substantially as set forth, of a combustion-chamber having an opening at its top, a vertical wall or partition dividing 65 said chamber into two compartments communicating at top, a grate located in the lower portion of each of said compartments, a steam-boiler covering the top of the combustion-chamber, a valve governing the passage of the 70 products of combustion through the tubes of the boiler, and a pair of regenerator-chambers each connected by a passage or channel with a compartment of the combustion-chamber below the grate thereof. 75

2. In an apparatus for the manufacture of gas, the combination, substantially as set forth, of a steam-boiler, a combustion-chamber divided by a wall or partition into two compartments communicating at top, a grate located in the lower portion of each of said compartments, a regenerator-chamber communicating with each of said compartments below the grate, each of said chambers being fitted with a discharge-valve, an air-blast valve controlling a pipe communicating with one of the regenerator-chambers, and a steam-supply valve controlling a pipe leading into the other regenerator-chamber. 85

3. In an apparatus for the manufacture of 90 gas, the combination, substantially as set forth, of a combustion-chamber having an upper throat or opening, a steam-boiler located above and covering said throat, a wall or partition dividing the combustion-chamber into two 95 compartments communicating at top, a grate located in the lower portion of each of said compartments, a regenerator-chamber communicating with each of said compartments below the grate, and pipes and valves governing the 100 traverse of a blast of air and a current of steam into and through the regenerator-chambers and compartments of the combustion-chamber.

BENJAMIN BRAZELLE.
